UNITED STATES PATENT OFFICE.

ADOLPH C. KLOPPING, OF TOLEDO, OHIO, ASSIGNEE OF ONE-HALF TO THE TOLEDO PARLOR FURNITURE COMPANY, OF TOLEDO, OHIO, A CORPORATION OF OHIO.

BED-DAVENPORT.

1,034,253.

Specification of Letters Patent. Patented July 30, 1912.

Application filed November 3, 1911. Serial No. 658,407.

To all whom it may concern:

Be it known that I, ADOLPH C. KLOPPING, a citizen of the United States, and a resident of Toledo, in the county of Lucas and State of Ohio, have invented a certain new and useful Bed-Davenport; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to bed-davports, and has particular reference to improvements upon the construction disclosed in my former United States Letters Patent No. 993,691, granted May 30, 1911.

20 The primary object of my invention is the provision of improved means in an apparatus of this class for controlling the folding and unfolding movements of the inner bed-frame section within the seat-frame, 25 whereby a more efficient and easily operable action of such part is obtained.

The invention is fully described in the following specification, and while in its broader aspect, it is capable of embodiment in numerous forms, a preferred embodiment thereof is illustrated in the accompanying drawings, in which,—

Figure 1 is an end elevation of a bed-davenport, with one end removed, the back 35 partly broken away and with the bed-frame in section and folded within the seat-frame. Fig. 2 is a section on the line $\alpha-\alpha$ in Fig. 1. Fig. 3 is a section of the davenport with the back in end elevation and open with parts 40 broken away, and with the seat-frame unfolded, and Fig. 4 is a cross section of the seat-frame in inverted position with the bed-frame parts in folded form therein and portions broken away.

45 Referring to the drawings, 1 designates one of the duplicate opposite ends of a davenport frame between which the back is mounted. This back is of hollow construction to facilitate the storing of bedding, pillows and the like therein and comprises the rear stationary part 2 attached in any suitable manner to the ends 1, and the forwardly and downwardly swinging front part 3 having the ends 4 and bottom piece 5. The front part 3 of the back is suspend-

ed for opening and closing movements relative to the back part 2 by a set of links 6, which are pivoted at their upper ends to the back part 2, as at 7, and at their lower ends to the front part 3, as at 8. The front part 60 3 is shown as having its lower end portion connected by a pair of links 9 to the back part 2, such links pivoting to the back part, as at 10, and the front part as at 11. A catch 12 serves to normally prevent an opening movement of the front 3.

The seat-frame of the davenport comprises the opposite ends 13, the front-piece 14 and the shallow back-piece 15, and is connected at its ends to the ends of the davenport frame by any suitable form of tumbling means, as well understood in the art.

The seat-frame carries the bed-frame, which is shown in the present instance as comprising the three major sections 16, 17 75 and 18, which are of substantially equal length and adapted to fold one another within the seat-frame, as indicated in Fig. 1, or be opened out into horizontal alignment, as indicated in Fig. 3. The sections 80 16 and 17 are pivotally connected at each side thereof by a pair of links 19, which are pivoted together upon a suitable support 20 rising from the back-piece 15 of the seat-frame when such frame is in inverted position, as indicated in Fig. 3, while the adjacent ends of the side portions of the sections 17 and 18 are foldably connected by links 21. Upon folding the bed-frame the outer section 18 is folded over the section 17 85 20 and the sections 17 and 18 are then folded over the inner section 16. As the sections 17 and 18 are folded over the section 16 the oppositely inclined inner ends 22 of the pairs of links 19 permit such links to move 95 slightly out of alignment, as indicated by the folded position of such links in Figs. 1 and 4, and then to act as a lever in lowering the attached end of the inner bed-frame section 16 within the seat-frame. For a fuller 100 explanation of the construction and folding and unfolding movements of the bed-frame, reference is made to my said former Letters Patent, which more fully discloses and describes the same.

105 One of the features of my present invention is to provide means for effecting a uniform lowering of the free end of the inner bed-frame section 16 with the inner or pivoted end thereof during the folding 110

operation of the bed-frame, which means is more efficient and positive in its operation than the means shown and described in my said former Letters Patent for such purpose. To accomplish this I provide a slotted guide link 23 within the seat-frame at each end thereof, which links are pivoted at one end to the respective ends of the seat-frame, as at 24, and have their other ends pivoted, as at 25, to the inner ends of bars or links 26, the outer ends of which links pivot to the outer ones of the associated bed-frame links 19 adjacent to the inner ends thereof, as at 27. Each side bar of the bed-frame section 16 has a stud 28 projecting from the outer side thereof and working within the guide slot of the link 23. The arrangement of the guide links 23 and their connection through the bars 26 with the bed-frame links 19 is such that when the bed-frame is in the unfolded position shown in Fig. 3, the links 23 will be raised into proper position to support the free end of the bed-frame section 16 in horizontal alinement with the other unfolded sections of the frame, while upon folding the bed-frame the folding movements of the outer links 19 will lower the free ends of the guide links 23 through the medium of the links 26 in such proportion that the free end of the bed-frame section 16 will be permitted to lower by gravity within the seat-frame at the same speed as the inner end of such section, as is apparent by reference to Fig. 4. This means for controlling the movements of the inner bed-frame section 16 within the seat-frame during the folding or unfolding movements of the bed-frame is found in practice to be very efficient in its operation and to materially improve upon the means heretofore employed for such purpose.

In order to rigidly space the outer bed-frame section 18 and its supporting legs 29 from the sections 16 and 17 when folded therebetween, as indicated in Fig. 1, I pivotally attach one end of a catch member 30 to each supporting leg 29 at the outer end of the bed-frame, as at 31, and suitably mount a catch finger 32 thereon to coöperate therewith to engage a stud or pin 33 projecting from the outer side of the bed-frame section 17. The catches 30-32, when engaged with the respective studs 33 of the bed-frame section 17, serve not only to rigidly retain the outer and intermediate bed-frame sections in rigid spaced relation when folded within the seat frame to prevent a rattling of the section 18 within other bed-frame parts when the usual mattress and bedding are omitted from between the sections, but also firmly hold the legs 29 in folded relation to the bed-frame section 18, as is apparent. Upon inverting the seat-frame to the position shown in Figs. 3 and 4, the operator can insert his hand within the bed-

frame to move the catch parts 30 to release the engaged studs 33, or this may be accomplished when the bed-frame sections 18 and 17 have been unfolded, after which the section 18 can be unfolded from the section 17 and the legs 29 lowered to support the outer end of the frame.

It is apparent that with my improvements I have provided a bed-davenport which is more easily operated and of greater practicability and commercial value than davenports of this class heretofore used, and is also of simple and inexpensive construction.

I wish it understood that my invention is not limited to any specific construction or arrangement of the parts except in so far as such limitations are specified in the claims.

Having thus described my invention, what I claim as new and desire to secure by Letters Patent is,—

85

1. In an article of the class described, an invertible seat-frame, a bed-frame having at least two major sections in pivotal link connection, a support pivotally carrying said connection, a guide member pivotally attached to the inner side of an end of the seat-frame and having a slot in which a part of one of said major sections slidingly works, and means for imparting pivotal movements to said member from a movement of said link connection.

90

2. In an article of the class described, an invertible seat-frame, a bed-frame having at least two major sections in pivotal link connection and foldable one over the other, the inner section having lowering movements within the seat-frame upon a folding of the bed-frame and vice versa, said connection forming minor bed-frame sections and being pivotally carried by parts of the seat frame, a member pivoted to each end of the seat-frame and having a slot in which a part of the inner bed-frame section works to cause a raising or lowering thereof when the member is pivotally moved, and a bar pivotally connecting the free end of each member to the associated connection between the bed-frame sections for imparting predetermined movements to the member when said connection is turned on its pivot.

115

3. In an article of the class described, an invertible seat-frame, a bed-frame having at least two major sections and a pair of links forming minor sections and pivotally connecting each side of such sections, said links having their inner ends pivoted together to a rear portion of the seat-frame and being capable of slight relative pivotal movements, a slotted member pivoted to each end of the seat-frame adjacent the upper front portion thereof, a stud projecting from each side of the inner bed-frame section adjacent to its inner end and working in the slot of the associated member whereby pivotal movements of the members impart rais-

120

125

130

ing and lowering movements to the inner end of such section, and a bar pivotally connecting the free end of each member to the outer one of the associated pair of links adjacent to its pivot, to impart predetermined movements to the members from folding or unfolding movements of said links.

In testimony whereof, I have hereunto signed my name to this specification in the presence of two subscribing witnesses.

ADOLPH C. KLOPPING.
